Patented May 31, 1921.

INVENTOR:

William F. Beatty,

BY John E. Jones,

ATTORNEY.

UNITED STATES PATENT OFFICE.

WILLIAM FRANKLIN BEATTY, OF CINCINNATI, OHIO.

DESIGN FOR A SODA-FOUNTAIN AND ICE-CREAM-DISPENSING APPARATUS.

58,011.

Specification for Design.

Patented May 31, 1921.

Application filed March 22, 1920. Serial No. 367,885. Term of patent 14 years.

To all whom it may concern:

Be it known that I, WILLIAM F. BEATTY, a citizen of the United States, residing at Cincinnati, in the county of Hamilton and State of Ohio, have invented a new, original, and ornamental Design for a Soda-Fountain and Ice-Cream-Dispensing Apparatus, of which the following is a specification, reference being had to the accompanying drawing, forming part thereof.

The figure is a front or face perspective view of a soda-fountain and ice-cream dispensing apparatus, showing my new design.

I claim:

The ornamental design for a soda-fountain and ice-cream dispensing apparatus, as shown.

WILLIAM FRANKLIN BEATTY.
